CLAIM

The ornamental design for a pistol charging handle, as
shown and described.

DESCRIPTION

FIG. 1 shows a pistol charging handle in an environmental
use configuration with a handgun that is shown in dashed
lines.

FIG. 2 shows an isolated and enlarged perspective view of
the pistol charging handle of our new design in the same
orientation as FIG. 1.

FIG. 3 shows a top view of our new design.

FIG. 4 shows a rear view of our new design.

FIG. 5 shows a bottom view of our new design.

FIG. 6 shows a front view of our new design.

FIG. 7 shows a right side view of our new design. The left
side is a mirror image thereof; and,

FIG. 8 shows a front, top perspective view of the pistol
charging handle of our new design.

Dashed lines in FIG. 1 depict environmental subject matter
that forms no part of the claimed design.
